KEY-OPENING CAN

Niels Johannes Haustrup, Tolderlundsvej, Odense,
Denmark; vested in the Alien Property Custodian

Application June 20, 1939, Serial No. 280,189
In Denmark July 4, 1938

2 Claims. (Cl. 220—54)

My invention relates to certain new and useful improvements in metallic cans or boxes of the type having a weakened line at which a portion at least of the can may be removed by means of a key on which the removable portion is wound and by which it is torn loose along the weakened line.

The present invention resides in the provision of a weakened line formed with a Z-shaped curve to provide two inter-projecting tongues, one of which may easily be bent inwardly and detached sufficiently to permit insertion of a specially formed key that also comprises a part of my invention.

Further, the invention resides in the provision of a pair of spaced grooves or ridges between which a prong of the key lies when in position for opening the can or box and by which the key is kept in place while starting the tear and during the rolling up of the cover.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawing, in which:

Fig. 1 is a top plan view of a can or box embodying my invention.

Fig. 2 is a similar view of the same after the insertion of the key.

Fig. 3 is a similar view showing the top partly removed to expose the contents of the can.

Fig. 4 is an edge elevation of one form of key.

Fig. 5 is an elevation of the same, looking from right to left in Fig. 4.

Fig. 6 is a detail section showing how a key may be used to bend down and detach the tongue 7 from the cover for insertion of a key.

Fig. 7 is a view similar to Fig. 6, showing another form of key and showing the tongue 7 detached from the cover.

In the drawing, in which like numbers and letters of reference indicate like parts in all the figures, 1 is the top of the box which is seamed at 3 to the body 2 of the box in the usual way. The top 1 is provided with a weakened line 5 conforming generally to the outline of the box, and at one corner (preferably) the line 5 assumes a Z-shaped curve, thereby to provide two tongues 6 and 7 extending in opposite directions, the tongue 6 being part of that portion 4 of the

top which is to be removed, while tongue 7 is a part of the top 1 which remains on the body 2. That part of the weakened line 5 which outlines the tongue 7 is preferably weaker than the remainder, so that upon applying pressure against the top of tongue 7 by a key or other suitable instrument tongue 7 may first be torn loose and bent in (see Fig. 7) so that the longer tang 13 of the key 10 may be inserted under the top part 4 between the parallel ridges 8 and 9, while the shorter tang 12 lies over the top part 4, as shown in Fig. 2.

After inserting the key, as shown in Fig. 2, and turning it counter-clockwise, the portion 4 of the top 1 may be torn loose and rolled up, as shown in Fig. 3.

Several forms of keys are shown, all of which, however, have a forked end constituted by the spaced tangs 12, 13, or 12^a, 13^a, and all including a rod portion 10, or 10^a or 10^b, and a loop 11, 11^a or 11^b, as the case may be.

All forms also preferably have their tangs bevel-cut as at 14, 14^a or 14^b, as the case may be, so that if desired the sharp edges of tang 13^a can be used to pierce the weakened line between tongue 7 and the top portion 4 in inserting the key.

The simplest form of key is that shown in Figs. 2 to 5, inclusive.

The key shown in Fig. 6 has a sharpened end 16 to its loop 11^b and is shaped to permit placing that end under the bead 3, while a portion 17 of the key is bent to form a toe 17 to press down on tongue 7 when the key is used as a lever with 16 as the fulcrum. The key is further bent to form a heel 18 which by contact with the portion 4 of the top 1 serves to limit the swing of the key-lever.

The key of Fig. 7 simply has the toe 15 and its rod 10^a lies straight so that its forked end 12^a—13^a will serve, by contacting the top part 4, as a stop.

The manner of use and the advantages of the invention will be clear to those skilled in the art.

What I claim is:

1. A generally rectangular can having curved corners and having a top provided with a continuous weakened tear-line adjacent and following the margin of the can throughout substantially its entire length, a portion of said line which is adjacent one corner of the can being of the outline of a curved Z to form two tongues, one of which extends in one direction and the other of which extends in the opposite direction, the directions in which the tongues extend being diagonally across said corner, one tongue being permanently attached to the can and the other being

an integral part of that part of the cover which is to be torn loose.

2. A generally rectangular can having curved corners and having a top provided with a continuous weakened tear-line adjacent and following the margin of the can throughout substantially its entire length, a portion of said line which is adjacent one corner of the can being of the outline of a curved Z to form two tongues, one of which extends in one direction and the other of which extends in the opposite direction, the

directions in which the tongues extend being diagonally across said corner, one tongue being permanently attached to the can and the other being an integral part of that part of the cover which is to be torn loose, that portion of the cover which is to be removed having parallel spaced ribs, the space between said ribs lining up with the permanent tongue to receive a key between the ribs by which key the can is to be opened.
